UNITED STATES PATENT OFFICE.

GEORGE E. OAKLEY, OF ALBANY, NEW YORK, ASSIGNOR TO CONSOLIDATED CAR-HEATING COMPANY, OF ALBANY, NEW YORK, A CORPORATION OF WEST VIRGINIA.

CAR-DOOR CONTROL.

Application filed May 8, 1920. Serial No. 379,868.

To all whom it may concern:

- Be it known that I, GEORGE E. OAKLEY, a citizen of the United States, residing at Albany, in the county of Albany and State of New York, have invented certain new and useful Improvements in Car-Door Controls, the following being a full, clear, and exact disclosure of the one form of my invention which I at present deem preferable.
- For a detailed description of the present form of my invention, reference may be had to the following specification and to the accompanying drawing forming a part thereof, wherein
- Fig. 1 is an elementary diagram of the door wiring and
- Fig. 2 shows the full wiring for one direction of door movement on one side of the car, together with the associated wiring for the buzzers and signals.
- In the control of car doors on the so-called "multiple-unit" system it is at times desirable that one man should operate the doors of only two or three cars of the train, the rest of the cars being divided into similar groups or operating units each having its doors operated by one man. Of course, in that event it is necessary to employ for each group a train wire which will be of suitable length for the particular group to which it pertains and for that purpose the train wire or wires of the entire train will be interrupted at intervals to form the desired sections. It is also an old expedient in this art to transfer the action of one circuit to a succeeding circuit by means of a relay magnet, so that the two circuits remain electrically insulated although the action of one circuit is continued into the other through the relay magnet. I make use of these expedients by providing two relays on each car, either one of which may control the door-engine magnets of all the doors on one side of the car. These two relays are located respectively in train wires entering the car from opposite ends. These train wires are thus permanently insulated from each other at this point and constitute the adjacent ends of sections extending into the next adjacent cars on each side. A doorman stationed at an intermediate point where he can operate switches in both of two adjoining sections will be able to control the doors in an adjacent car on either side of the car on which he is stationed and also the doors of his own car. By this means a doorman can control the doors of three cars constituting an operating unit of the train, he himself being stationed at the middle of the unit. The system is limited to three-car units, but it has the advantage that in making up the train, it is not necessary to open the train wire at each second, third, or fourth car according to the number of cars that may be selected as the operating unit, since it will be permanently sectioned by my arrangement, the section-ends being permanently located at the middle of each car by the separation at the relays.
- Referring to Fig. 1 which illustrates the elementary principle of my arrangement, three adjoining cars are shown therein, which constitute an operating unit. B, B and C, C represent two train-wire sections extending from the middle of the center car to the middle of the next car on either side. A and D represent idle half-sections. It will be assumed that the doorman is stationed on the middle car and from that point is to operate the doors on all three cars. To distinguish the operating car for purpose of description it may be designated as a "sending car," the other two being "receiving" cars. The circuits on all cars will normally be set so that they will act as receiving cars, but when the doorman enters a car to use it as a sending car, he throws certain switches therein to set it for its sending function, and on leaving it again will set it back into receiving condition. Thus in the middle car switches X and Y are open, while switch Z is closed; but on the two end cars, switches X and Y are closed, while switch Z is open.
- If now the doorman on the middle car presses button 1, he will establish a circuit from battery H, by the closed switch Z to wire B, B, leading to the rear (left) car and there it will pass, by the now closed switch Y, to the lower contacts of relay P, thence to relay K and ground. That will energize relay K which will in turn establish a separate circuit from battery H to magnet W and ground. The said magnet W here represents the door-engine-controlling magnet of a car door on this rear car; ordinarily there will be several doors and several magnets W

of which the single one here shown is typical and representative. By this means the doorman on the middle car can close, or open, the doors on the rear car.

5 If he next presses button 3, he will establish a circuit from battery H, through closed switch Z, as before, to the wire C, C, leading into the next car ahead where it will pass through the now closed switch X to 10 relay P and to ground. The relay P will thereupon act to close a separate local circuit from battery H, through its upper contacts to relay K and thence to ground and relay K will act, just as in the rear car, to 15 close a circuit from battery H to magnet W and ground. Thus the doorman has operated the doors in the forward car (right).

If he finally presses button 2 he will energize magnet W of his own car, the circuit going from battery H, by switch Z, as before, to contacts of button 2 and thence through magnet W to ground. The switches X and Y are merely for the purpose of enabling the doorman to operate 25 the doors on his own car separately from those on the other two cars. They may be omitted and the doors on the sending car put under the control of button 1 or button 2; whichever button acted first would energize relay K at the sending as well as at 30 the receiving car.

It will be evident that it is the switch Z 35 that establishes the battery connection for all three buttons, that switch being therefore closed at the sending car but open at the two receiving cars. Moreover, it is the switch X that connects line C, C to the relay P on the forward receiving car, and switch Y that connects line B, B to the relay K on the rear receiving car. Hence those switches X and Y are closed at the receiving cars but open at the sending car. At the rear receiving car, also, the circuit through acting relay K is separate from 40 the circuit through relay P and does not affect that relay. On the other hand at the forward receiving car relay P is the acting relay and its circuit is separate from and does not affect relay K, except through the 45 relay contacts which are in a separate local circuit that includes the relay K. Therefore the doorman on the middle sending car can only control the doors on one car ahead and on one car behind in addition to the doors on his own car. His range of control 50 can not reach into a second car ahead or a second car behind. In effect the train line sections are of but one-car length, although lapping over the adjacent halves of 55 two cars. These sections are isolated from each other on all three cars by the relays, and on the sending car by the switches X and Y also. This operating unit of three cars will be repeated throughout the train, 60 the total number of cars being a multiple 65

of three, e. g., nine cars. If a tenth car is added it will require an additional doorman. The setting-up switch, for putting the door circuits on any car in condition to act on a sending car, will involve only the 70 contacts at X, Y and Z. It is, of course, an old practice in these multiple unit systems to provide such a setting-up switch for arranging the circuit-connections according to the sending or receiving function of any 75 car in the train. For instance in the control of the propelling motors, it is the car where the motorman is stationed that is thus set up to act as a sending car.

In Fig. 2 a single car equipped for my 80 system is shown in fuller detail together with certain associated circuits for signaling purposes, one feature of which is to so arrange the door-closing signal that it will identify the sending cars by a light on the 85 side of the car which will burn so long as the doors are closed.

At E is indicated the setting-up switch aforesaid including the individual switches X, Y, Z. Such switches are usually of the 90 drum type and in this figure the rectangles in full lines represent contact plates on the drum as they stand when the switch is set for a sending car, X and Y then being away from their respective line terminals and Z 95 being engaged therewith, the dotted lines showing the position of these plates when set in the normal, receiving-car position. In this Fig. 2 the supply wires for battery 100 H are distinguished by small crosses, and the train wires are in heavier lines. Obviously the closure of switch Z provides a battery connection for button switches 1, 2 and 3; the opening of switch X breaks the connection between line B and relay P, and the 105 opening of switch Y breaks the connection between line C and relay K. In Fig. 2 the button-switch 2 and relay K are provided with two contacts additional to the contact shown in Fig. 1, so as to deliver battery 110 current to three door-engine magnets W¹, W² and W³, it being assumed that the car has three doors on one side of the car. Moreover, in Fig. 1 a battery H is, for 115 simplicity, indicated at each point where current is required, while in practice, a single battery is used with wires leading therefrom to each of said points, as shown in Fig. 2. Otherwise the showing of the door-controlling circuits is the same as in Fig. 1. 120

The door-signal wire is shown at S. This is the usual signal wire now in general use which extends from end to end of the car passing in succession through contacts d¹, d², d³ at each of the several doors, which contacts are opened by the doors when they start to close. When all the doors are shut the circuit of this wire is completed and the signal thereby given to the motorman to go 125 ahead. I interpolate in this wire, at each 130

car, a relay M which becomes energized when the doors are all shut and thereby closes the circuit of two red lamps, one on each side of the car, at the middle side door in each sending car. This relay M is shown in Fig. 2 as connected to wire S between the points a and b. Between said points a and b a shunt or by-pass connection for short-circuiting the interpolated relay M is provided which connection will be interrupted at each sending car but remain intact at each receiving car. Thereby when the signal circuit is completed by the closing of all the doors the said relays M in said signal circuit will be short-circuited, by the shunt or by-pass connection, at each receiving car when the said connection is intact, but will become energized at each sending car when the said connection is interrupted. For thus interrupting or leaving intact the aforesaid short-circuiting connection, setting-up switches are provided on each car, these being additional to the setting-up switch E which only serves for the door-controlling circuits. All of the setting-up switches are to be operated manually by the operator upon entering and leaving the car which may be selected as a sending car, and in some cases the switches E and F for one side of the car may be operated together. In Fig. 2 I have shown two setting-up switches at F and G, one for each side of the car, at either one of which the short circuit around relay M can be broken when the switch is turned to set the apparatus into sending condition. Thus the aforesaid short-circuiting connection for relay M starts at the point b and, after leaving point b, goes to terminals 5 and 4 of setting-up switch G, which terminals engaged by plate V¹, and thence to terminals 8 and 9 of setting-up switch F, which are shown as separated by the withdrawal therefrom of the plate V², and thence to the point a. The opening of this circuit at points 8 and 9, obviously breaks the short-circuit around relay M. For the doors on the other side of the car, the control-circuits for which are not shown herein since they merely duplicate those which are shown, this short-circuit for relay M would be broken by setting-up switch G, instead of F which would remain closed. This arrangement removes from the signal wire S the resistance of all the relays M which are on the receiving cars, and also identifies the sending cars at which alone the lamps are lighted while the doors are closed. The contacts operated by the relay M establish a connection from the battery to contact point 10 whence the current branches to the lamps L¹ and L², one on each side of and outside of the sending car at the middle door. When any door of the series is open the lamps are extinguished. By this means each doorman and outside platform man will get the same signal as the motorman, and will

know that the doors have been properly closed.

The buzzer signal, by which one doorman communicates with the next, employs the wire T. This wire is interrupted at each doorman's station, either at terminals 11 and 12 and plate U¹ on setting-up switch G or at terminals 6 and 7 and plate U² on setting-up switch F. Then if the doorman presses switch button O¹, he will close a circuit from the battery to wire 14 and thence to wire T which extends unbroken through the two receiving cars at the left to the next sending car where it will operate the buzzer Q² in that car, going thence to ground. But if the doorman presses button O² the current will go to wire 15 and thence by wire T through the cars to the right, and in the next sending car will operate buzzer Q¹. While the pressing of button O² will incidentally operate buzzer Q² in the same car it is of no consequence because the operator knows that it is caused by his own action and that it is not a signal from the next operator ahead of him. The essential feature is that it will not operate buzzer Q¹ in the same car, because the buzzer train-line T is now interrupted, either at contacts 11 and 12 of setting up switch G, if the apparatus on one side of the car is in use, or at contacts 6 and 7 of setting-up switch F if that on the other side of the car is in use. The current caused to flow by pressing button O² will pass, as heretofore stated, from the battery-wire to said button O² and thence by wire 15 to the buzzer train wire T. Thence it will go to the next car ahead (i. e. to the right in Figure 2). It can not go to the car behind because the line T is broken on this sending car by the switch F or the switch G. On the said car ahead the current will go, as will be seen at the left end of Fig. 2, to the setting-up switches F and G, which will be closed since this next car ahead is a receiving car. Incidentally it will operate both of the buzzers on that car, which is of no consequence, because it is a receiving car carrying no operator. From said switches F and G it will proceed, by wire T, to and through the second car ahead, which is also a receiving car, and thence to the third car ahead which is the next sending car. There it will enter, as at the left end of Fig. 2, by the wire T and operate the buzzer Q¹, but will not pass the setting-up switches F and G which will be open, and will therefore not operate buzzer Q². Hence the operator on this next sending car will recognize the operation of his buzzer Q¹ as a signal from the next operator in the rear. In precisely the same way the operator in the car of Fig. 2 can signal to the next operator behind him in the third car back, who will receive such signal on his buzzer Q², while his buzzer Q¹ will not be affected because he has broken the line T at

one of his setting-up switches F and G. By this means the doormen can, as is now the practice, pass the door-closing signal from one to another through the train, although 5 they are now three cars apart instead of one car apart.

For the doors on the one side of the car which is herein illustrated, the setting-up switches E and F will be used, while for 10 the doors on the other side (not illustrated) the switch G, together with a switch like E, will be employed. Since such setting-up switches are old, for any combination of circuits which may be appropriate for putting a 15 car in sending condition, I make no claim to them.

What I claim as new and desire to secure by Letters Patent is:

1. A train door system comprising operating magnets for the door engines, two relay magnets on each car, either of which controls the same door-engine magnets and a train-line having sections extending into the same car and containing respectively the two 25 relay magnets aforesaid.

2. A train door system comprising operating magnets for the door-engines, two relays on each car, either of which controls the same door-engine magnet, a train-line having sections extending into the same car and containing respectively the two relays aforesaid, and operating switches for two of 30 said sections located at their adjoining ends.

3. A train door system comprising control 35 magnets for the door-engines of three cars which constitute an operating unit, train-wire sections extending from the middle car into each end car, operating switches for said sections located on the middle car, and two

relays in each section located respectively on 40 adjoining cars and each controlling the door-engines of the car in which it is located.

4. A train door system comprising control magnets for the door-engines, a train-line 45 permanently sectional at each car by relays either one of which may operate the control magnets on one car, and operating switches for each of two sections at their adjacent ends.

5. A train door system comprising control 50 magnets for the door engines, a train-line permanently sectioned at each car by relays either one of which relays may operate the door magnets on one car, operating switches for each of two sections at their adjacent 55 ends, and a third operating switch at the same point for separately operating the door magnets of the car on which the said switches are located.

6. A train door system comprising control 60 magnets for the door-engine, two relay magnets one in each of two adjoining train-line sections both controlling the same door-engine magnet and contacts in the circuit of one relay magnet controlled by the other. 65

7. A train door system comprising a series 70 of control magnets for the several door engines, a sectional train-line for said magnets, operators' switches for each train-line section, a signal at each operator's station, a signal circuit containing contacts in series controlled by the movement of the respective doors, signal-controlling relays in said circuit at each car and short-circuiting switches 75 for the several relays.

Signed at Albany, county of Albany, State of New York, this 30th day of April, 1920.

GEORGE E. OAKLEY.
